ELECTRICAL CONNECTOR HOUSING

Friedrich Josef Alois Kourimsky, Leutershausen, Germany, assignor to AMP Incorporated, Harrisburg, Pa.

Filed Oct. 20, 1970, Ser. No. 25,575

Term of patent 14 years

Int. Cl. D13—03

U.S. Cl. D26—1

FIG. 1 is a front perspective view from above and one side of an electrical connector housing showing my new design;

FIG. 2 is an elevational view of the other side of the housing of FIG. 1;

FIG. 3 is a rear elevational view of the housing;

FIG. 4 is a perspective view of the housing of FIG. 1 showing the two parts in their unassembled condition; and FIG. 5 is a bottom plan view of the housing.

I claim:

The ornamental design for an electrical connector housing, substantially as shown and described.
